UNITED STATES PATENT OFFICE.

WILLIAM B. DOE, OF SKYLAND, NORTH CAROLINA, ASSIGNOR OF ONE-HALF TO EDWIN W. GROVE, OF ST. LOUIS, MISSOURI.

WALL BOARD.

Application filed April 6, 1923. Serial No. 630,368.

To all whom it may concern:

Be it known that I, WILLIAM B. Doe, a citizen of the United States of America, a resident of Skyland, in the county of Buncombe, State of North Carolina, have invented certain new and useful Improvements in Wall Boards, of which the following is a full, clear, and exact description, reference being had to the accompanying 10 drawings, forming a part of this specification.

This invention relates to improvements in wall boards, one of the objects being to provide a simple, effective and inexpensive 15 means for securing and supporting a coat of plaster.

Prior to this invention, the ordinary method of plastering walls has consisted in first applying a thick rough coat of plaster to 20 laths, a large percentage of this plaster being forced between the laths and permitted to drop on the inner faces thereof, so as to anchor the body of plaster on the wall.

After this has been done, the surface of 25 the first coat is usually scratched by means of suitable tools to form a rough surface on which the finishing coat of plaster is applied.

One of the objects of my invention is to 30 dispense with the laths as well as the thick coat of plaster which is ordinarily applied to the laths, thereby eliminating a number of expensive elements including the initial cost of the laths, the labor of securing 35 numerous small laths to the wall frame, and the labor and expense of the rough coat of plaster which is usually carefully applied to the laths and then scratched to form the rough surface. As a substitute for these 40 various items, I have produced relatively large wall boards that can be easily and quickly secured to the wall frame, and each of these boards has a novel plaster-receiving 45 face adapted to receive and securely hold the single coat of plaster which is ordinarily applied as a finishing coat over the rough surface of an initial coat.

To set forth one form of the invention, I have shown and will hereafter describe a 50 wall board consisting of a mass of strong, coarse and irregular fibers surrounded by a body of pithy substance. The plaster-receiving face of this board is provided with numerous ribs and grooves formed in the

mass of fibers and pithy substance and 55 adapted to receive and hold the plaster. The coarse fibers are preferably severed and displaced at the grooves, so as to withdraw ends of the fibers from the pithy substance, thereby forming numerous irregular anchoring 60 elements which securely hold the single coat of plaster.

I have found that the boards consisting of a mass of large fibers enclosed by a body 65 of pithy substance can be conveniently obtained at a low cost by cutting palmetto trees, or palm trees, into slabs of suitable dimensions. The logs of this unique wood consist of a pithy substance enclosing large, 70 strong fibers, and for this reason have only a relatively small commercial value, but when formed into wall boards according to the present invention, the products can be most advantageously used to obtain the results herein pointed out. 75

Fig. I is a longitudinal section of a machine adapted for use in making the wall boards.

Fig. II is a transverse section of the machine. 80

Fig. III is a perspective view of a wall board embodying the features of this invention.

Fig. IV is an enlarged section showing a portion of the wall board and one of the 85 grooves therein.

To illustrate one form of the invention, I have shown a wall board A having a plaster-receiving face provided with alternating ribs and grooves 1 and 2, respectively, formed longitudinally of the board. These ribs and grooves are preferably formed in straight parallel lines extending throughout the length of the board. 90

The board preferably consists of a mass 95 of coarse, irregular fibers 3 surrounded by a body of pithy substance 4, as shown most clearly by Fig. IV. The fibers have end portions which extend from the pithy substance at the ribs and grooves, and more 100 particularly at the walls of the grooves, as suggested by Fig. IV. The ribs 1, grooves 2 and the extended ends of the large fibers 3 cooperate with each other to securely anchor the plaster on the wall board. 105

The method of making the board preferably includes the step of cutting and pulling portions of the fibers, so as to withdraw

end portions of the fibers from the pithy substance, thereby forming numerous small irregular anchoring stems for the plaster, and this step of the method can be conveniently performed while the grooves 2 are being formed in the mass of fibers and pith.

As an illustration of a suitable machine for carrying out this method, I have shown a table 5 equipped with upper feed rolls 6, lower feed rolls 7, a pressure roll 8 between the upper feed rolls, and a gang of circular saws 9 below the pressure roll 8. The rolls 6 and 8 are mounted in bearings 10 (Fig. II) adapted to slide vertically in frames 11. Springs 12 are seated upon the bearings to force the rolls 6 and 8 onto the board A, at the same time forcing said board onto the lower rolls 7, while the pressure roll 8 retains the board in proper engagement with the gang of saws.

The springs 12 may be adjusted by means of screws 13 engaging spring seats 14 at the upper ends of the springs.

The saws 9 are secured to a shaft 15 which may be rotated by any suitable mechanism, and the upper edges of the saws project slightly above the top face of table 5, so as to form the grooves in the board A, the latter being fed by the rolls 6, 7 and 8 which are rotated in the directions indicated by arrows in Fig. I.

The board passing through the machine is acted upon by the saws which form the grooves 2, at the same time cutting and displacing the fibers at the grooves in such a manner that the fibers are severed and the resultant end portions withdrawn from the pithy substance to form numerous anchoring elements, as suggested by Fig. IV.

I claim:

1. A wall board having a plaster-receiving face provided with grooves to receive portions of the plaster, and numerous coarse irregular fibers surrounded by the body portion of said board and having end portions extending from walls of said grooves to anchor the plaster. 45

2. A wall board comprising a body of pithy substance having a plaster-receiving face and numerous coarse fibers surrounded by said pithy substance, said fibers being severed to provide end portions whereby the plaster is anchored, and said end portions being extended from said body of pithy substance. 50

3. A wall board comprising a body of pithy substance and coarse fibers surrounded thereby, said board having a plaster-receiving face provided with grooves to receive portions of the plaster, and said coarse fibers being provided with end portions projecting from the pithy substance at said grooves to anchor the plaster. 55

4. A wall board comprising a body of pithy substance having a plaster-receiving face and numerous coarse irregular fibers surrounded by said body of pithy substance, said plaster-receiving face being provided with alternating ribs and grooves formed in the mass of fibers and pithy substance, 60 and said fibers being provided with end portions extending from the pithy substance at said ribs and grooves to serve as anchors for the plaster. 70

In testimony that I claim the foregoing 75 I hereunto affix my signature.

WILLIAM B. DOE.
